UNITED STATES PATENT OFFICE.

JONATHAN PETERSON, OF BROOKLYN, NEW YORK, ASSIGNOR TO COMBINATION
MACHINE COMPANY, OF NEW YORK, N. Y., A CORPORATION OF DELAWARE.

LABELING MACHINE.

Application filed February 8, 1921. Serial No. 448,370.

To all whom it may concern:

Be it known that I, JONATHAN PETERSON, a citizen of the United States, and resident of Brooklyn, in the county of Kings and State of New York, have invented certain new and useful Improvements in Labeling Machines, of which the following is a specification.

The present invention relates to a labeling machine and more particularly to a machine for applying labels and stamps about the walls of cartons or containers and has special reference to the provision of a machine of this type operating on gangs or rows of 10 containers for quantity production.

The principal objects of my invention include, in addition to the provision of a machine of this type operating upon rows of containers and in which the row formation 20 of the containers is maintained through all the operating steps of the machine for purposes of permitting subsequent handling of the containers in like row formation, the further provision of a coordinated machine 25 in which rows of labels are fed in a novel and efficient manner for receiving an adhesive coating and for conveyance to a label applying station; the provision of a labeling machine in which the labels are selected 30 from a supply station in a novel and efficient manner and in which such labels are deposited or delivered for receiving an adhesive coating while minimizing the liability 35 of adhesive attaching to the various parts of the machine; the still further provision of a labeling machine in which rows of containers are handled in a novel manner for label application and for container conveyance; the provision of a coordinated machine 40 of relatively simple design consistent with the manifold functions involved which shall feed labels, coat them with adhesive, feed containers, apply labels to the walls of the containers and affix stamps over the labelled containers and the further provision 45 of a machine for performing the above recited functions in a rapid manner for purposes of quantity production, many of the parts of operating cycles on successive rows 50 of containers taking place simultaneously for the effecting of a large capacity output.

To the accomplishment of the foregoing and such other objects as may hereinafter appear, my invention consists in the elements and their relation one to the other, as

hereinafter particularly described and sought to be defined in the claims, reference being had to the accompanying drawings which show a preferred embodiment of my invention and in which—

Figure 1 is a front elevational view of the labeling machine, parts being broken away,

Figure 2 is a top plan view of the same with the container carrier removed and other parts broken away,

Figure 3 is a cross sectional view on the line 3—3 Figure 2, showing the container supply magazine and feed,

Figure 4 is a cross sectional view on the line 4—4, Figure 1, showing among other things, the label feeding means and the adhesive coating means,

Figure 5 is a fragmentary top plan view of Figure 4 showing the label magazine and parts of the label feeding means,

Figure 6 is a rear view of the label feeding means taken on the line 6—6, Figure 2,

Figure 7 is a fragmentary detail view of the label picker showing the manner of selection of labels from the label magazine.

Figure 8 is another fragmentary detail view of the label feeding means showing the label transfer mechanism about to remove the labels from the picker,

Figure 9 is a detail view of the label supply magazine,

Figure 10 is a view of the apparatus taken along lines 10—10 Figure 2, parts being shown in section, this figure also disclosing label feeding means and the adhesive gumming means in association with the label conveying means,

Figure 11 is an enlarged front elevational view of a portion of the machine shown in Figure 1, showing the container feeding means in particular, the said view being substantially the portion of the machine shown between section lines 12 and 14 of Figure 1,

Figure 12 is a cross sectional view taken along the lines 12—12, Figure 1, such view being substantially a right elevational view of the mechanism shown in Figure 11,

Figure 13 is a cross sectional view of my machine taken on the line 13—13, Figure 2 and showing the container conveying means and the stamp affixing mechanism,

Figure 14 is a view taken on the line 14—14 Figure 1 and showing the container carrier and the container conveying means,

Figure 15 is a detail view of a releasing

mechanism used in connection with container conveying,

Figure 16 is a cross sectional view on the line 16—16, Figure 13, showing the stamp affixing apparatus, and

Figures 17 to 27 are diagrammatic views showing the series of operative steps performed by my machine on the labels, containers, and stamps in the production of labelled and stamped containers.

Before entering into a detailed description of my invention, I will briefly state that I have illustrated herein a gang machine capable of simultaneously operating at a plurality of stations on rows of cartons or containers for affixing labels thereto and preferably about the side walls thereof and for further affixing stamps over the applied labels. The machine illustrated herein is capable of applying labels over a plurality of faces of a container and where a container having cylindrical walls is used, as herein disclosed, the machine is constructed to apply the labels around the cylindrical walls of the container, the ends of the labels being affixed in abutting or overlapping relation, the stamps being preferably applied over the said abutting or overlapping label ends. The machine is intended for operation on gangs or rows of containers and in order to clearly understand the invention I will describe a complete cycle of operation of one of said gangs or rows, although it will be understood, as will further appear hereinafter, that parts of operating cycles on successive rows of containers take place simultaneously for the purpose of providing a high capacity output machine.

In the preferred form shown herein a series or row of stacks of labels are stored in a magazine at a label supply station, a label feeding means being provided for selecting and segregating a row of labels at a time, one label from each stack, and for transferring such labels to a label conveying means which, in turn, convey the labels to a label applying station. The label feeding means which selects the labels from the supply station and transfers them to the conveyer is of a novel construction and although in the preferred form I have shown such means as adapted to be used on rows of labels, it will be understood that the novel constructional features involved are not limited to such use but may be used with individual label feeding. The label feeding means herein generally designated as B, reference being now had to the diagrammatic Figures 17 to 20 of the drawings, comprises pneumatically controlled elements operating for selecting labels from the label supply station or magazine A, the feeding means comprising a selector or picker 30 movable to and from the magazine, as indicated by the arrow in Figure

17, and a pneumatic transfer mechanism 31 cooperating therewith. The said picker is pneumatically controlled for the selecting of a row of labels from the bottom of the series of stacks in the magazine A, Figure 17 of the drawings indicating the movement of the picker towards the magazine for the selection of one of such labels. After a label *l* has been selected from the picker, the picker moves downwardly away from the magazine, the transfer mechanism 31 being then moved horizontally into position between the magazine and the picker in overlying relation to the picker, as shown in Figure 18 of the drawings. The picker 30 is then given a supplemental upward movement so that its suction face will be adjacent to the suction face of the pneumatic transfer mechanism, Figure 18 of the drawings showing the arrangement of parts prior to such supplemental movement. When the picker and transfer mechanism are in adjacent overlying relation the pneumatic action of the picker 30 is automatically cut off, suction being automatically supplied to the transfer mechanism 31, this action resulting in the removal of labels *l* from the picker, the labels adhering to the suction face of the transfer device 31. The transfer mechanism and the labels thereon are then moved horizontally in the opposite direction, as shown in Figure 19, and in overlying relation to the label conveying means C. The said conveying means comprises a series of endless belts 32', 32² and 32³, being herein shown as three in number, these belts being coated with zones of adhesive 33', 33² and 33³ respectively, such adhesive constituting glue, paste or the like, which is applied to the belts while in motion over adhesive applying rollers 34', 34² and 34³ of an adhesive applying mechanism D. The endless belts are intermittently moved over tables 35', 35² and 35³, these tables being movable vertically, as indicated by the arrows in Figure 19 of the drawings. When the transfer mechanism is positioned in overlying relation to the coated belts and tables and during the period of dwell of the intermittently movable belts, the tables are given a slight upward movement for adjacent positioning with respect to the transfer mechanism 31. The pneumatic action of the transfer device is at such time automatically released, the label or labels *l* being thereby deposited on the adhesively coated conveyer belts. As will appear more in detail hereinafter, the suction face of the transfer device is so contoured as to prevent the "gumming up" of the said suction face during the co-action between the transfer mechanism and the coated belts, such suction face moreover being complementary to a contoured suction face of the picker, which facilitates

segregating of the label from the magazine, as will appear more in detail hereinafter. Means is also provided operating in the event of improper selection of the label or labels by the picker or in the event of improper removal of such label or labels by the transfer mechanism or both to prevent cooperation of the transfer mechanism and the coated conveyer so as to eliminate the liability of the transfer mechanism coming in direct contact with the coated belts with consequent "gumming up" of the former. Figure 20 of the drawings shows the label positioned on the coated conveyer belts, the label as is obvious, receiving, due to such positioning, the adhesive on its under side. The conveyer belts with the labels thereon are then moved to a label applying station E, Figure 20^a, a movable belt 32² being made to disappear at a point in advance of the station E, the remaining belts 32' and 32³ spacedly supporting the labels thereon, as indicated in said Figure 20^a. The said belts 32² and 32³ at the label supplying station are movable over additional tables 36' and 36², these tables being adapted to be reciprocated in a vertical direction, as indicated by the arrows in the said Figure 20^a. Rows of containers *c* are then fed from a container supply station by means of a continuously movable endless belt conveying means 37 to the label applying station E, a reciprocating plunger means 38 being supplied for moving a row of these containers upwardly in the space between the space belts 32' and 32³ for label application. The containers are thus moved in an upward direction and in contact with substantially the central portion of the labels *l* on the conveyers, further upward motion of the containers effecting removal of the labels from the conveyers, as shown in Figure 21 of the drawings. At this time the tables 36' and 36² are given their upward motion for the adjacent positioning of these tables with respect to the resilient elements 39 positioned above the label ends, these resilient elements coming into contact with the label ends for the resisting of withdrawal of these label ends from the conveyer belts. At the same time a gripper means 40 comes in contact with the top of the container, the gripper means 40 in association with the plunger 38 firmly holding the container in position during label application, the withdrawal resisting means 39 serving the double function of effecting close application contact of the label on the containers and causing the labels to wipe all available glue or adhesive from the label conveyer. During this upward movement of the containers and the labels, brush elements 41 positioned in the path of such movement aid in partially applying the labels about the walls of the container, the label ends remaining unapplied as shown in Figure 22 of the drawings. The upward movement of the plunger 38 feeds the containers in a rotating carrier or turret, means being provided for locking the containers in position to permit the return movement of the plunger 38 and the simultaneous movement of the tables 36' and 36², as shown in Figure 22 of the drawings. The containers with the labels partially applied are then moved in the carrier in the direction indicated by the arrow in Figure 22, the partially applied labels meeting a rotating brush 42, one end of the label being fixed to the container by this brush, as diagrammatically indicated in Figure 23. The brush 42 is then given a downward movement to prevent the brush coming in contact with the unapplied label end for the prevention of label removal from the container. In the further movement of the partially labelled container a brush 43 normally out of the path of such movement is oscillated in a direction indicated by the arrow in Figure 24, such oscillation resulting in the application or the affixing of the other label end on the container in juxtaposition to either in abutting or overlying relation with respect to the first label end. The labelled containers are then carried by the rotating turret to a discharge station where the row of labelled containers is moved by a transfer means to a gumming station F, as shown in Figure 25 of the drawings, this gumming means applying adhesive to a portion of the labelled containers, as indicated in the said figure. Further movement of the row of labelled containers brings such row to a stamp affixing station G, shown in Figure 26 of the drawings, where a plurality of stamps are fed from a stamp supply station 43' by means of a stamp feeding means 44 in underlying relation to said row of labelled containers, movement of the said feeding means 44 causing the affixing of the stamps to the gummed labels on the containers. The row of labelled containers is then fed to other machines for further packaging operations, a completed container showing the affixed label and the affixed stamp thereon being shown in perspective in Figure 27 of the drawings.

I will now describe in detail the preferred apparatus, carrying out the various operative steps outlined above.

The magazine and label feeding means.

Referring now to Figures 1 and 2 showing the general arrangement of the apparatus and to Figures 4 to 9 showing in detail the magazine and the label feeding means, the magazine A and the label feeding means B and their operating parts are shown supported on standards 45 and plate 46, mount-

ed upon the supporting base 47 of the apparatus. The label supply station A comprises a magazine having a plurality of spaced walls 47' defining a plurality of elongated pockets 48, in which are placed a plurality of stacks or piles of labels 7. Plates 49 are attached to the under side of these walls 48, these plates providing lips protruding in the path of label movement and normally supporting the stacks of labels. The magazine A is supported by trunnions 50, movable in open end bearings 51 on the framework 52, this construction permitting the removal of a magazine and the replacement of a filled magazine therefor. The labels are fed from the bottom of the piles, it being understood that the supply in the pockets 48 may be replenished by filling such new supply from the top of the magazine A. The label feeding means, as described in the brief outline above, comprises preferably a reciprocable picker 30 movable to and from the magazine A and a horizontally reciprocable transfer mechanism 31 movable to and from the picker 30. The picker 30 comprises a suction box supported by the plate 53, the said plate being vertically movable in opposed guides 54, mounted on the supporting plate 46, a cam follower 47² being journaled in the bottom of the said plate 53 for coaction with a cam to be hereinafter described. The picker or suction box 30 is provided with a plurality of selecting elements 55, arranged in parallel relationship, each selecting element being provided with a plurality of suction ports 56 opening into the unitary suction chamber 57, formed in the suction box 30. Each selecting element comprises a longitudinal portion having a preferably concave suction face, as clearly shown in Figure 7 of the drawings, the concavity of this face functioning when the selecting elements are in a position shown in Figure 7 for selecting the bottom labels from the stack of labels to permit curling of the bottom label to facilitate withdrawal and segregation thereof from under the protruding lips of the plate 49 and out of the supply pockets 48. After the selecting operation of the labels, the labels lie flat in curled position about the concave suction face of the selecting elements, resisting any curling of the labels in other directions. The picker 30 with the labels thereon is then moved vertically downward as indicated by the arrow in Figure 7 and into position, as shown in Figure 8 of the drawings.

The transfer mechanism 31 also comprises a suction box having the suction chamber 58, the said suction box being provided with a plurality of removing elements 59, each of these elements having a plurality of ports 60 in open communication with the suction chamber 58, these removing elements 59 hav-

ing suction faces with a contour complementary to the contour of the suction faces of the selecting elements 55, in the present instance such contour being convex in shape. The transfer mechanism 31 is movable in guides 61 formed in the stationary framework of the device, the transfer mechanism being movable into overlying relationship with respect to the picker 30 when the picker 30 is in its descending position, as shown for example, in Figures 4 and 8 of the drawings. When in this position the picker 30 is given a supplemental upward movement to permit cooperating contact of the selecting elements 55 and the removing elements 59 with the labels therebetween for the purpose of removing the labels from the picker elements and to the transfer mechanism. Flexible pipe elements 62 and 63 are provided and are connected for communication with the suction chambers 57 and 58 respectively.

Means are provided for operating the label feeding means in the manner above described, such means comprising a cam 64 mounted on the main driving shaft 65, the said cam being provided with a major cam surface 66 and a supplemental cam surface 67, the major surface 66 cooperating with the cam follower 47² for moving the plate 53 and the picker mounted thereon towards the magazine A for the label selecting operation, the weight of the picker and the plate permitting downward motion of these elements after label selection. Connected also to the main shaft 65 is a crank arm 68, the said crank arm being connected by means of a link 69 to one arm of a lever 70, pivoted on the frame of the machine, the other arm of the lever 70 being connected as by means of link 71 to a crank arm 72 for oscillating a shaft 73 connected to said crank arm 72, a pin and slot connection 74 being provided between the crank arm 72 and the link 71 for the purpose of finely adjusting the throw of the oscillating shaft 73 and the parts attached thereto. To the shaft 73, attention being specially called to Figures 4 and 6 of the drawings, are connected opposed segmental gears 74' meshing with racks 75, arranged in parallel, the said racks being connected to the transfer mechanism 31, the racks having flanges movable in the guides 61 for guiding the horizontal reciprocation of the transfer mechanism 31. It will be apparent that in the rotation of the main shaft 65, the transfer mechanism 31 is horizontally reciprocated by means of the connections described, such reciprocation moving the transfer mechanism to and from overlying position with respect to the picker 30. When the parts are in the position shown in Figures 4 and 8 of the drawings the supplemental cam surface 67 of the cam 64 comes into activity for the supplemental

upward movement of the picker 30 to position said picker closely adjacent to the transfer mechanism for the purpose hereinbefore referred to in detail.

- 5 For the purpose of facilitating the removal of the labels from the picker, a suction releasing device is supplied, such releasing device comprising a weighted lever 76, pivotally mounted on the picker 30, one 10 arm of the said lever 76 overlying an airport 77 opening into the suction box 57. One of the segmental gears 74' shown to the right of Figure 6 is provided with an angle iron 78 which, when the parts are in 15 the position shown in Figure 8 of the drawings, overlies a hook portion 79 of the lever 76. It will be apparent that in the supplemental movement given to the plate 53 and the picker 30 when the parts are positioned as shown in Figure 8 of the drawings, the hook portion 79 and the lever 76 will engage the angle iron 78, rocking the lever 76 against the gravitational action of the weight attached thereto, opening the port 77 20 to atmosphere and permitting release of the suction effective at the ports 56, this action permitting removal of the labels from the picker. At this time also the suction is cut off from the pneumatic picker 30 and suction 25 is applied automatically by means herein-after to be described, to the transfer mechanism 31, this action resulting in the adhesion of the labels to the transfer mechanism for subsequent removal to the conveying means, 30 to be described presently.

The label conveying and adhesive coating mechanism.

- Referring to Figures 1 and 2, showing the 40 general arrangement of parts of the apparatus and more particularly to Figures 4, 5 and 10 of the drawings, the label conveying means comprise the endless belts 32', 32² and 32³, hereinbefore referred to, the said 45 endless belts moving over the drums or pulleys 80 and 81 journaled on opposite ends of the base plate 47 of the machine and in standards 82 and 83 respectively, mounted on the said base plate 47. The drums are 50 connected for movement in unison by means of a sprocket chain 84, trained over sprockets 85 and 86 mounted on shafts 87 and 88 respectively, as shown for example in Figure 2 of the drawings, these shafts carrying 55 the drums or pulleys 80 and 81. The endless belts, in their motion about the drums 80 and 81, have lower and upper flights, the outer surface of these belts being adapted to receive an adhesive coating 60 during their lower flight position, the upper flights of the conveyer belts being adapted for conveying the labels received from the label feeding means to a label applying station. The central belt 32², in contradistinction to the other belts, which latter are

trained over the opposed drums 80 and 81, moves over pulleys 85' and 86' journaled in standards 87', mounted on the base plate 47, as shown for example, in Figures 1 and 10 of the drawings, this arrangement permitting the disappearance of the central belt between the label receiving station and the label applying station, the labels being thereafter supported by the spaced conveying belts 32' and 32³, the space between 75 these belts being provided for a purpose to appear hereinafter. In operation it has been found that the labels will adhere to the spaced belts 32' and 32³ sufficiently to permit the movement of the middle belt out of contact with the supported labels.

Means is provided for coating the outer surface of the conveyer belts with zones of adhesive, such means being generally designated as D and shown more particularly in Figures 1, 4 and 10 of the drawings. To this end an adhesive bath 88' is provided, which is supported on the base plate 47 of the machine, a series of stirrers or agitators 89 being provided in the said bath for securing and retaining the proper consistency of the glue or paste contained therein. Spaced rollers 90', 90² and 90³ are mounted on a shaft 91 and are movable while immersed in the bath 88, the said rollers moving in synchronism with the gumming rollers 34', 34² and 34³ hereinbefore referred to, the said gumming rollers receiving a coating of adhesive from the rollers 90' to 90³. The gumming rollers 34', etc., may be mounted 100 on a shaft 92, journaled in arms 93, pivoted to a stationary part of the frame, adjusting means 94, being preferably provided to adjust the degree of contact between the rollers 90', etc. and 34', etc. The conveyer belts 105 32', 32² and 32³ move over and in contact with the gumming rollers 34', etc., such movement resulting in the transferring of adhesive from the gumming rollers to the outer surface of the belts in a manner as 110 will be apparent, a presser roll 95 being preferably provided, as shown particularly in Figures 4 and 10 of the drawings, to press the moving belts in secure contact with the gumming rollers 34' etc.

Means is provided for operating the adhesive coating means D, such coating means being actuated by movement of the drum carrying shaft 88. The said shaft is provided with a gear 96 meshing with a pinion 97 on the stub shaft 98, the said shaft being provided with a sprocket 99, over which is trained a sprocket chain 100, the said sprocket chain moving over a second sprocket 101 fixed on the roller shaft 92, the said 125 roller shaft being also provided with a pinion 102 meshing with a pinion 103 fixed to the roller shaft 91. By this means movement of the drum 81 transmits motion to the coating means and more particularly to the 130

coating rollers for the consequent coating of adhesive on the conveyer belts 32', 32² and 32³.

The conveyer belts are intermittently operated, intermittent motion being supplied to the drum 80 and transmitted to the drum 81. Such intermittent motion may be obtained by means of a Geneva gear 104, the star wheel 105 of which is fixedly mounted on the drum shaft 87, the pin wheel 106 of the Geneva gear being mounted on a stub shaft 107 journalled in a standard 108, the said stub shaft being provided with a bevelled pinion 109 meshing with another bevelled pinion 110 fixedly mounted on the main shaft 65. As will be apparent in the rotation of the main shaft 65, which receives motion from a main sprocket chain 111, movable over a sprocket wheel 112, fixed to the main shaft, intermittent motion will be supplied by means of the Geneva gear 104 to the drum shaft 87 and to the drum 80, this motion being transmitted to the drum 81 for intermittent movement of the conveyer belts 32', 32², and 32³.

For the purpose of providing a smoothly operating machine and to overcome the inertia of starting movement in the Geneva gear, I provide means for continuously supplying moving impulses to the drum shaft 87. To this end I supply a pulley 113, loosely mounted on the shaft 87, the said pulley having a friction face and friction pads 114 contacting a friction disk 115 fixed to the said shaft 87, a spring 116 being provided to urge the loosely mounted pulley 113 for frictional contact against the disk 115. Power is supplied to the pulley 113 by means of a belt 117, the belt being given continuous motion. As will be apparent, the frictional coaction of the pulley 113 and the disk 115 continuously tends to rotate the disk and the intermittently movable shaft 87, overcoming any starting inertia therefrom after periods of dwell in the said intermittent movement, this minimizing vibrations in the machine.

The conveyer belts are movable over the tables 35', 35² and 35³ hereinbefore referred to, the said tables being located at the station where the labels are deposited from the transfer mechanism 31 onto the conveyer belts. These tables are mounted on plungers 118 resiliently movable in the base 119, springs 120 encircling the plungers being provided to permit resilient engagement between tables and belts and the transfer mechanism 31. The base 119 which supports the tables is mounted on a plate 121, the said plate having flanges 122, movable in guides 123, formed in the supporting brackets 124, these brackets being supported in any convenient manner on the supporting plate 46, as more clearly shown in Figures 4 and 10 of the drawings. The supporting plate 121 is forked, as at 125, a cam follower

126 being journalled in the forks 125, the cam follower cooperating with an operating cam, as will hereinafter appear, to effect vertical reciprocation of the base 119 and tables and belts supported thereon. When the transfer mechanism 31 is in a position shown diagrammatically in Figure 19 of the drawings the tables are given an upward movement as hereinbefore described to bring the conveyer belts in close proximity to the labels on the transfer mechanism 31 to effect the removal of the labels from the transfer mechanism and the depositing of the same on the conveyer belts.

Means is provided for releasing the pneumatic control in the transfer mechanism 31 to permit the depositing of the labels on the coated conveyer belts, such means preferably comprising elements mounted to move respectively with the transfer mechanism and the tables, such releasing means being effective during the movement of the tables with respect to the transfer mechanism. Such means takes the form, in my present invention, of an arm 127, having a projecting finger 128, mounted on the table 35' and movable therewith and an arm 129 pivotally mounted on the transfer mechanism 31, the said arm 129 overlying a port 130 communicating with the suction chamber 58 and opening the said suction chamber to atmosphere when the arm 129 is lifted against its own weight. When the transfer mechanism is in the position indicated in Figure 19 of the drawings, upward movement of the tables 35' etc., and the consequent upward movement of the finger 128 causes the raising of the arm 129 which overlies the finger 128 and the consequent opening of the suction chamber 58 to atmosphere, this resulting in the release of the labels on the transfer mechanism and the depositing thereof on the conveyer belts 32' etc. In the return movement of the transfer mechanism, the arm 129 moves over the port 130 by gravity, an element 131 being also preferably provided in the path of movement of the said arm 129 to positively return the said arm into position in overlying relation with the port 130. It will be noted that the release of the pneumatic control transfer mechanism is effected by the final positioning of the table with respect to the transfer mechanism and that the elements effectuating the release are mounted for movement with the transfer mechanism and the table. Similarly it will be noted that the release of the pneumatic control of the picker mechanism hereinbefore described is also effected by the final positioning of the picker mechanism with respect to the transfer mechanism, the elements effectuating the release being also mounted for movement on the movable picker mechanism and with the movable transfer mechanism.

The means for reciprocating the table support 119 preferably comprises a cam 132 mounted on a shaft 133, the said cam being provided with a cam surface 134, adapted for coaction with the cam follower 126 for moving the table support 119 upwardly, the weight of the parts effecting the downward motion of the said support when the cam face 134 moves out of contact with the cam follower 126. The shaft 133 is journalled in the supporting brackets 124, a clutch sleeve 135 being loosely mounted on the said shaft 133, the said sleeve being provided with a sprocket 136, over which is trained a sprocket chain 137, the said sprocket chain being also trained over a sprocket wheel 138 fixedly mounted on the main shaft 65. Keyed to the shaft 133 for sliding movement thereon is a grooved wheel 139, the said wheel being provided with clutch teeth cooperating with recesses in the sleeve 135, as shown in dotted lines in Figure 10 of the drawings, a spring 140 encircling the shaft 133 being provided for moving the wheel 139 and its clutch teeth out of clutch engagement with the sleeve 135. Means is provided for throwing this clutch into operation against the action of spring 140, such means comprising a pivoted yoke 141 provided with pins 142 projecting in the grooved wheel 139, the said yoke being provided with a projection 143, in which is mounted a pin 144, to which pin is connected a link 145, connected in turn to a lever 146, fulcrumed on a stationary portion of the structure, as shown in Figure 10 of the drawings. As will be obvious, in moving the lever 146 the clutch elements 139 and 135 will be brought into operative engagement by means of the intermediate connections described. Means is provided for locking this clutch in operative engagement, such means comprising a latch 147 pivotally mounted on stationarily mounted arm 148, fixed to any desired part of the machine, as will be apparent from Figure 10 of the drawings. In moving the yoke 141 to the right for causing operative engagement of the clutch faces with the clutch elements, the latch 147 will gravitationally engage the pin 144 and retain the elements in operative engagement.

As heretofore pointed out, the suction faces of the transfer mechanism are made convex for proper cooperation with the concave suction faces of the picker mechanism, the convex suction faces of the transfer mechanism also functioning for minimizing the liability of adhesive on the conveyer belts reaching the suction faces, with the consequent gumming up thereof. Means is also provided for automatically throwing out of operation the means for reciprocating the table support 119 in the event of failure of the picker mechanism to select one or more labels from the magazine or in

the event of failure of the transfer mechanism to remove its full quota of labels from the picker. As will be apparent, if the transfer mechanism fails to obtain a full row of labels, the upward movement of the table support 119 and the tables thereon will result in producing contact engagement between the coated conveyers and the suction faces of the transfer mechanism, with the consequent gumming up of the latter. To prevent this, means for throwing out of operation the elements which move the table support 119 is provided. Such means broadly comprises elements for releasing the latch 147 and permitting the spring 140 to throw the grooved wheel 139 into inactive position and thus unclutching the shaft 133 from the main shaft 65. To this end I provide an operating arm 149, pivoted to the framework of the machine and movable in grooved guide 150 (see Figure 10), the said arm being connected by means of a link 151 to a bell crank lever 152, fulcrumed on any stationary part of the machine, which lever is connected by means of a link 153 to a lever 154, fulcrumed on a projection 155 (see particularly Figures 4, 5 and 10 of the drawings), one arm of the said lever being provided with a cammed stop 156, rearward motion of the lever as seen from Figure 5 being limited by the stop pin 157 mounted on the projection 155. Mounted preferably centrally on the transfer mechanism 31 is a dash pot 158, the said dash pot being provided with a plunger 159, telescoping within the tubular member 160, a spring 161 being provided for urging the plunger 159 outwardly, a stop 162 being provided for limiting the outward motion of the plunger 159, the face of said plunger being preferably provided with a cam surface 163. The tubular member 160 is in open communication by means of a port 162' (see Figure 5) with the suction chamber 58 of the transfer mechanism 31. As will be apparent, if a full row of labels is received by the transfer mechanism, the suction in the suction box 58 operates to move the plunger 159 inwardly against the action of the spring 161. The transfer mechanism in its reciprocation when the plunger 159 is thus inwardly positioned moving past the lever 154 without actuating the same. In the event, however, of improper selection or removal of the labels resulting in the failure of the transfer mechanism conveying its full row of labels, the suction will be operative at the ports of the missing label and will fail to move the plunger 159 inwardly, the said plunger being then in the position shown in Figure 5 of the drawings, and urged outwardly by the spring 161. With the parts so related and during movement of the transfer mechanism from the magazine A and towards alinement with the conveyer belts, the plunger 159 en-

gages the stop 156, moving the lever 154 in clockwise direction, as viewed in Figure 5, this motion causing the upward movement of the arm 149 by means of the intermediate 5 connections described above, such upward movement of the arm 149 engaging latch 147 for the releasing of the clutch elements 135 and 139, this in turn stopping the operation and the consequent upward movement of the 10 tables supporting the conveyer belts. It will further be apparent that the transfer mechanism continues its reciprocation rearwardly towards the magazine A, the cam face 163 on the plunger 159 and the cam face on the 15 projection 156 slidably cooperating to permit the rearward motion. In this state of affairs the operator may stop the machine if in the subsequent operation improper selection of removal of labels continues. Means 20 may also be provided for manually actuating the clutch releasing elements to stop the operation of the movable table and such means may consist of a handle 165 mounted on the arm 149.

25 The means for pneumatically controlling the operation of the picker and the transfer mechanism is shown, for example, in Figures 2 and 6 of the drawings, such means comprising a stationary control drum 167 hung from 30 the plate 46 of the machine on a hanger 168, a pipe section 169 communicating with the interior of the said drum being connected to a suction exhaust (not shown). Rotatably mounted in hangers 170 is a shaft 171 and to 35 this shaft is fixed a frustrated cone 172, having a segmental orifice 173 cooperating with a port 174, provided in a drum 175, having a tapered inner surface in close contact with the tapered surface of the cone portion 172. 40 A pipe section 176 communicates with the port 174, the said pipe section being connected to the flexible pipe section 62, connected to the picker mechanism 30. As will be apparent in the rotation of shaft 171 and the cone 45 172, when the segmental orifice 173 moves over the port 174 the suction box of the picker will be open to the exhaust 169 for the pneumatic actuation of the said picker simultaneously and in timed relation with 50 the pneumatic control of the said picker. The pneumatic elements generally designated as 177 and located at the opposite end of the shaft 171, control the pneumatic actuation of the transfer mechanism 31 in properly timed synchronism with the pneumatic control of the picker 30. Means for rotating the shaft 171 may comprise a sprocket wheel 178 mounted on said shaft and connected to a sprocket wheel 179 on the main shaft 65, 55 the sprocket wheels being connected by means of the sprocket chain 180 (see Figure 6).

60 It will be understood from the foregoing that by the means described above a 65 row of labels is fed to the conveyer belts

from the magazine A by the feeding means B, these conveyer belts being coated by coating mechanism D to effect application of adhesive to the under side of the labels received by said conveyer belts, the conveyer 70 belts delivering a row of labels to a label applying station presently to be described in detail.

Container feeding and label application. 75

The labelled conveyers described above, after receiving the labels from the label feeding means, transfer these labels to the label applying station E, the endless conveyers when the labels reach the said station 80 E assuming a stationary period of its intermittent travel. To the said label applying station E are fed containers c in rows means being provided for feeding such containers to the label applying station. Such 85 means in the present form of my invention takes the form of an endless belt feeder 37, referred to above and shown, for example, in Figures 2 and 12 of the drawings, the said belt 37 moving over opposed pulleys 181 and 182, the shaft 183 of the pulley 182 being provided with a gear 184 meshing with a gear 185 (see Figures 11 and 12 of the drawings), the said gear 185 being fixed to a shaft 186, journalled in the machine, the said shaft 186 having also mounted thereon a sprocket 187, over which is trained a sprocket chain 188 moving over a sprocket 189 mounted on the main shaft 65, attention being called to Figures 11 and 12 of the drawings. As will be apparent, in the motion of shaft 65, continuous motion is applied to the pulley shaft 183 and consequently to the endless belt feeder 37, this motion of the feeder tending to move the containers into position on the plunger 38 at the label applying station, as will be presently described. Means is also provided for supplying containers in rows to the feeding belt 37, such means being shown particularly in 110 Figures 2 and 3 of the drawings and comprises a rotatable cage 190 rotatable as shown by the arrows in Figure 3 of the drawings, the said cage being mounted in opposed brackets 191 fixed to the framework of the machine, rows of containers placed in a series of troughs 192 being inserted in the cage 190. The said cage is then rotated counterclockwise, as viewed in Figure 3, and the now inverted troughs with 115 the containers are moved into position on the moving belt 37, the troughs 192 being then removed, permitting the series of rows of containers c to be moved by the belt 37 towards the label applying station. 120

125 For application of the labels to the containers, the containers as briefly referred to above, are moved into registration contact with the labels on the conveyers, movement of the containers withdrawing 130

the labels from the conveyers, means being provided in the path of such movement for partially and securely applying the labels about the walls of the containers.

5 To this end I have provided a reciprocable plunger 38, referred to above, the said plunger being properly contoured at its top in conformity with the contour of the containers, the plunger 38 being thus 10 adapted to support a row of containers, as clearly shown in Figure 12 of the drawings, the plunger being movable in opposed guides 193 formed in opposed standards 194, which are mounted on the base plate 47 of the machine, the said plunger being provided at opposite sides with racks 195, shown, for example, in Figure 12 of the drawings. The said plunger is adapted to reciprocate in a vertical direction for receiving a row of 15 containers and moving such row of containers through the space between the spaced conveyers 32' and 32² and into registration contact with the labels on the conveyers, the upward movement of plunger and containers 20 thereon moving the labels from off the conveyer, means being provided during this movement for securely applying the major portion of the label about the walls of the container.

25 30 The means for reciprocating plunger 38 may comprise opposed oscillatable segmental gears 196, meshing with the racks 195, the said gears being mounted on shaft 197, to which is affixed a crank arm 198, connected by means of a link 199 to another crank arm 200, affixed to the shaft 186 referred to above. As will be apparent, on rotation of shaft 186 (see Figure 12, for example) shaft 197 will be oscillated, rocking the 35 40 segmental gear 196 for the reciprocation of racks 195 and the plunger 38 to which they are attached. For the purpose of preventing the movable plunger 38 from interfering with the positioning of successive rows of containers on the feeder 37, a spring actuated gate 201 is supplied, the said gate being mounted on rods 202 slidable in brackets 203 fixed to the standards 194, the said rods being provided with abutments 45 50 55 60 65 70 75 80 85 90 95 100 105 110 115 120 125 204 fixed thereon, compression springs 205 encircling the rods 202 and seated against the upper abutments 204 and against the brackets 203. Upon the downward movement of the plunger 38 the bottom wall of plate 206 of the plunger engages the top abutments 204, this engagement positively moving the gate 201 downwardly permitting a row of containers to be fed onto the plunger 38, the said row being stopped against further movement by a stationary stop gate 207. Upon the upward movement of plunger 38 the compressed springs 205 urge the gate upwardly, a stop 208 on the said gate limiting the upward movement of

the said gate with respect to the containers 65 on the feeding belt 37.

For the purpose of securely applying the body of the labels about the walls of the container I preferably provide means for gripping the containers during their upward movement and means for resisting label withdrawal activity, such latter means being adapted to resiliently engage the label ends during withdrawal of the labels from the conveyers by the containers. To 70 75 80 85 90 95 100 105 110 115 120 125 this end I provide gravitationally actuated gripper means 40, mounted on the container carrier to be referred to hereinafter, the said gripper 40 being situated in opposed relation to the plunger 38, the cooperation of these elements securely holding a row of containers during the upward movement thereof to effect efficient label application thereto. To resist withdrawal of the labels I provide resilient means for holding the label ends during the withdrawal of the labels, this resulting in securely wrapping the body of the label about the walls of the container for efficient affixing of the label to the container, such means comprising resilient elements 39 referred to above in connection with Figures 20^a, 21 and 22 and shown in Figure 12 of the drawings, the said resilient elements or fingers being normally out of contact with the label conveyers and the labels thereon to permit freedom of movement of the labels on the said conveyers. During the label withdrawal activity the resilient elements 39 are adapted to come in contact with the ends of the labels for the purpose of securely holding these labels and resisting withdrawal activity. To this end I provide the tables 36' and 36² briefly referred to above in connection with Figure 20^a of the drawings, the conveyers 32' etc., being movable over these tables at the label applying station. These tables 36' and 36² are pivoted at one end thereof to the frame of the machine, as at 210 (see for example Figures 1 and 10 of the drawings), the other end of the tables being supported by spring pressed plungers 211 which are, in turn, supported on a base plate 212 formed preferably integrally with a post 213 (see Figures 11 and 12), which may be adjustably mounted as by sleeve 214 to an arm 215 pivoted to a lever 216, fulcrumed as at 217 on a bracket 218, mounted on the base plate 47 of the machine, the said lever 216 being also connected to an oscillating lever 219 having a yoke 220 provided with an elongated recess, the minor diameter of which fittingly encircles the main shaft 65, reference being had to Figure 12 of the drawings. The shaft 65 is provided at this point with a cam 221, the said cam having a raised cam surface 222 adapted for engagement with a

roller 223 mounted on the yoke 220. As will be apparent, in the rotation of the main shaft 65, the cam surface 222 of the cam 221 will engage the roller 223 for the upward reciprocation of the plate 212 and for the upward movement of the tables 36' and 36² mounted thereon. It will be further apparent that the downward movement of the tables is provided by the weight of the parts when the low point of cam 221 is opposite the roller 223. The tables are given this upward motion during label withdrawal activity, the upward motion of the tables resulting in cooperative contact of the resilient elements 39 with the label ends for withdrawal resisting activity.

Means is provided during movement of the containers and labels through the space between the spaced conveyers for brushing the labels on the containers to assist application of the labels to the containers, such means comprising brush elements 224, preferably mounted above the resilient elements 39, these brushes functioning to apply the labels about the walls of the containers except for the ends of the labels, which remain hanging on the container, such ends being at the bottom of the container, viewed in the position shown in Figures 12 and 22 of the drawings.

Container conveying and stamp affixing.

The rows of containers are movable by the plunger into a container conveyer or a carrier in the form of a turret 225, now to be described. The turret comprises preferably two opposed disks 226 and 227 mounted on a shaft 228, journaled in upstanding brackets 229 and 230, each of the disks 226 and 227 being provided with a series of circumferentially spaced heads 231 and 232, the containers being adapted, as will appear presently, to be held in position on the turret for movement therewith by the said heads 231 and 232. The shaft 228 is also provided with an enlarged portion 233 having a plurality of radial bores which receive the plurality of stems 234, spaced circumferentially about the shaft, these stems supporting the gripper means 40 referred to above. The plunger 38 is adapted to move a row of containers and the labels thereon into the turret 225 and between a set of opposed heads 231 and 232. Means is provided for removing the pressure of the gripper 40 so as to relieve downward strain on the containers prior to the downward movement of plunger 38 to permit the containers to be retained between the heads 231 and 232 securely in row formation, such means consisting preferably of a tubular post 235 shown in Figure 12, in which is movable a rod 236 having a stop 237, the said rod being connected to a lever 238, fulcrumed on a post 239, the said post be-

ing movable on a bracket arm 240 connected as at 241 to move with the plunger 38. The post 235 is provided with an angle iron stop 242, a spring 243 being provided, one end of which is seated on a flange forming part of the rod 236. The lever 238 is provided with a finger 239' for engaging a projection 240' mounted on the gripper 40. As will be apparent, when the plunger 38 reaches its uppermost position, rod 236, which is movable therewith by virtue of its being mounted on the post 235, is stopped by the engagement of the stop 237 with the top wall of the tube 235, this causing the upward movement of finger 239', actuating the projection 240' and moving the gripper 40 out of contact with the containers and against gravitation.

The heads 231 and 232 are then adapted for relative cooperation to engage the opposite walls of the end containers to securely hold a row of containers between the said heads. To this end the series of heads 231 are made axially movable in the disk 226, means being provided for locking these heads in container engaging position after container movement into the turret and means being further provided at a discharge station for unlocking the said heads to permit removal of a row of containers from the turret for further operation. These movable heads are shown in detail, for example, in Figure 11 of the drawings, and comprise a plunger rod 241', to which is attached the head 231, the said rod being provided with a flange portion 242, against which is seated a compression spring 243, the other end of the said spring being seated against the outer wall of the disk 226, the rod 241 and the spring 243 being housed in a tube 244, mounted on the said disk 226. The parts are so proportioned that in normal position the spring will move the rod 241' and the head attached thereto to the left, as viewed in Figure 11, permitting sufficient clearance between the opposed heads 231 and 232, this in turn permitting proper feeding of a row of containers into the turret. At the proper time the plunger 241' is moved inwardly against spring tension, a locking detent 245 mounted on the tube 244 being provided for engaging the flange 242 to retain the said plunger in the contracted position, as shown in Figure 11, the pressure of the head 231 on the containers and the resisting pressure of head 232 holding a row of containers securely in position on the turret.

Means is provided, properly timed with the operation of the other parts of the apparatus, to move the said plunger 241' into container engaging position, such means comprising, in the present form of the invention, a pneumatically controlled dash pot 246 having a spring retracted piston 247

and a piston rod 248 in alignment with the rod 241' and adapted to engage and move said rod for container engaging position, air compression means being supplied by 5 valve 177 for appropriately operating the piston 247. A spring 249 is provided for returning the piston and piston rod to starting position, this further permitting rotation of disk 226 with respect to piston 10 rod 248.

Means is provided for intermittently operating the turret 225, such means preferably comprising a Geneva gear, the star wheel 250 of which is fixed to the shaft 228, 15 the operating pin wheel 251 of which is connected to a shaft 252 journaled in an up-standing bracket 253, the said shaft being provided with a sprocket gear 254, over which is trained a sprocket 255, receiving 20 motion from the main shaft 65, as clearly shown in Figure 1 of the drawings. It will be understood that the intermittent motion of the turret is properly timed with the intermittent motion of the label convey- 25 ers cooperating therewith.

During intermittent motion of the turret, the ends of the labels are affixed in abutting or overlapping relation on the walls of the containers. To this end I provide 30 a continuously rotating brush 42, hereinabove referred to, this brush being positioned in the path of movement of the containers, as clearly shown, for example, in Figure 12 of the drawings. Figure 12 shows the upper label end of the container about to be affixed to the said container. The turret, as shown in Figure 12, is in its dwell position and upon the next movement of the said turret 225 the rotating brush 42, 40 coming in contact with the label end of the container, will sweep over the said end and wipe the label securely on the container. For the purpose of preventing the brush 42 from coming into contact with the other 45 end of the label of the container during further container movement, means is provided for moving the said brush 42 out of position out of the path of container movement. To this end the brush 42 is mounted 50 on the upstanding bracket 240, referred to above, the said bracket, as above indicated, being connected for reciprocation with the plunger 38. Thus, when the plunger 38 receives a downward motion with the turret in its rotating condition, brush 42 will move downwardly as well as rotate to apply one end of the label and escape the other end. In the further movement of the turret 225 the other end of the label is adapted 60 for application to the container by means of an oscillatable brush 43, referred to above. The said brush is mounted on a fixed arm 256, the brush being provided with a short arm 257 having a roller 258 at its end, 65 the normal positioning of the said brush

being shown in dotted lines in Figure 12 of the drawings for the purpose of preventing brush activity during movement of the container and the unattached end of the label past the said brush. When the unattached 70 end of the label reaches a position past the said brush a cam 259 forming part of a series of cam elements 259' and 259'', etc., and affixed to the turret 225 engages the roller 258 for the movement of the brush 43 over the unattached label end for the wiping of 75 said label end on the container to affix the same thereon.

After the labeling affixing operation the turret 225 carries the labeled containers to 80 a discharge station, the rows of labeled containers being then transferred for the stamp applying operation. Means is provided at the discharge station for releasing the locking head 231, said means comprising provisions for releasing the detent 245 to permit the spring 243 to, in turn, move the plunger 241' to retractive position. To this end I provide also a movable trough 85 oscillatable to and from the turret 225 to 90 receive the row of discharged containers, the movable trough comprising preferably a V-shaped trough 260 mounted on a plate 261, slideable on an inclined table 262, a detent releasing means 263 being mounted 95 to move with the said plate 261 and adapted to engage the detent 245 to move the same out of position for the release of the container retaining head 231.

Means is provided for slidably moving 100 the plate and the trough on the inclined table 262, such means comprising a yoke-shaped member 264 connected to said plate 261, one of the arms of said yoke 264 being connected to an operating lever 265 ful-crumed on the stationary part of the frame, as at 266, the other arm of said lever being connected to an arm 267, having a square 105 268 functioning as a cam follower and co-operating with the cam 269 fixed on the 110 main shaft 65. The other arm of the yoke 264 is connected preferably to a pivoted arm 270, mounted on the stationary part of the machine. As will be apparent, rotation of the main shaft 65 will move the 115 active surface of cam 269 into engagement with the follower 268, this in turn with the intermediate connections described, moving the plate 261 and the trough thereon to and from the turret 225, a weight 271 being 120 preferably provided to assist the weight of the parts from assuming a position away from the turret when the low point of the cam 269 is in contact with the cam follower 268. During the dwell period of the 125 turret 225 the parts are so timed that the slide 261 is moved towards the turret, actuating the release for permitting the movement of the row of containers into the trough 260, the trough being then moved downwardly 130

in alinement with other guide means to be presently described.

When the trough 260 reaches its descended position, means is provided for moving the row of containers longitudinally in the said trough and through other guide means in the form of troughs for the further gumming and stamp affixing operations. To this end I provide a series of pusher arms 272 rotatably mounted on a rod 273 arranged longitudinally of the machine, the said rod 273 being connected, as by means of a series of apertured lugs 274, to a longitudinally slideable rod 275, slideable in a series of brackets 276, attention being called, for example, to Figures 12, 13 and 14 of the drawings. The rod 275 is adapted to be actuated by an oscillating lever 277, fulcrumed as at 278 on the base 47 of the machine, a longitudinally disposed link 279 connecting the said lever 277 to a crank arm 280 fixed to the stub shaft 107 previously referred to. As will be apparent, on rotation of the shaft 107 through the intermediate connections described, rods 275 and 273 will be oscillated longitudinally of the machine, the pusher arms 272 when in the full line position shown in Figure 14 being adapted to move a row of containers from the trough 260 for the further necessary operations, it being understood, as shown in Figure 13 of the drawings, that a plurality of these pusher arms 272 are provided for the purpose of operating on a plurality of successive rows of containers for conveying them through the trough means to be described.

For the purpose of guiding the rows of containers for the further operation required, an elongated V-shaped trough 281 is provided, the bottom of said trough being cut away for a purpose presently to appear. The pusher arms 272 are each provided with a weight 282 for the purpose of normally positioning the pusher arm as shown in dotted lines in Figure 14 of the drawings. Means is provided, when a row of containers is to be fed through the troughs, for moving the pusher arms 272 to the full line position shown to permit the oscillating rod 273 in conjunction with the pusher arm 272 to accomplish the container moving operation. To this end I provide a plunger 283 slideable in a stationary part of the machine, as shown in Figure 13 for example, the said plunger being vertically alined with a pin 284 mounted on the rod 273, the alinement of these parts taking place when the rod 273 is in its extreme left hand position, as viewed in Figure 13. At this time the plunger 283 is adapted to be moved upwardly to engage the pin 284 to rotate the rod 273 and the pusher arms 272 thereon to cause the pusher arms to assume their operative position. The means for moving

the plunger 283 may comprise, for example, an arm 285 pivoted on a stationary portion of the machine, as at 286, the said arm being adapted to engage a cam 287 mounted on the main shaft 65, as shown, for example, in Figures 13 and 14 of the drawings. It will be understood that when the high point of the cam 287 contacts with the arm 285 the plunger 283 will be moved to effect positioning of the pusher arms 272 in the position shown, for example, in full lines in Figure 14. Means is provided for retaining the weighted arm 272 in its operative position, such means being shown, for example, in detail in Figure 15 of the drawings and comprises a cam ratchet 288 fixed to the rod 273 and cooperating with a pawl 289 pivotally mounted on one of the lugs 274, the pawl or detent 289 being adapted to engage the ratchet 288, as shown in Figure 15, to lock the pusher arm 272 in its active position. Means is provided, operative when the rods 273 and 275 reach the limit of their positions to the right as viewed in Figure 13, to unlatch the pawl 289 or detent 289 to permit the pusher arms 272 to move to their inactive position, as shown in dotted lines in Figure 14, such means comprising briefly a projection 290 in the path of movement of the pawl 289, engagement of these elements resulting in unlatching the ratchet 288, as will be clear by reference to said Figure 15 of the drawings. The cooperation of these elements will therefore move, as will be apparent, successive rows of containers from the trough 260 and through the elongated trough 281.

Stamp applying means.

The labelled containers are fed by the pusher means just described, past the gumming station F and a stamp applying station G. The gumming means at the said gumming station F comprises briefly a bath of adhesive 291, in which is rotatably mounted a gumming roller 292, adapted to contact the under side of the labelled containers, as clearly shown in Figure 13, when the said labelled containers are moved in the trough 281, the cut away portion of said trough permitting the contact between the gumming roller and the labels on the containers. The labels may be gummed at any desired portion but the parts of the apparatus are so arranged and constructed that the gumming takes place over the abutting or overlapping label ends. For the purpose of resisting the upward pressure of the gumming roller 292 I preferably provide a resisting rod 293 positioned in vertical alinement with the said gumming roller and above the trough 281.

The gummed labelled containers are then moved through the stamp affixing station G, a row of stamps at this stamp affixing

station being fed from a magazine and affixed to the row of labelled containers, a stamp being affixed to each container in proper registration contact therewith. The 5 stamp feeding means is particularly shown in Figure 16 of the drawings and comprises a stamp magazine 43' and a stamp feeder 44, referred to above. The feeder 44 is of a pneumatic type having a plurality of suction faces 294 for selecting stamps from the magazine 43 in a manner similar to the selection of the labels previously described, the contour of said suction faces 294 being also similar to the cylindrical contour of 10 the containers for the purpose of having these parts cooperate for effective stamp affixing. The feeder 44 is mounted on a plurality of longitudinally arranged supports 295 having substantially a semi-circular 15 movement to provide a horizontal and vertical movement between the magazine 43' and the trough 281. The means for moving the supports 295 in this manner may comprise sets of opposed disks 296 and 297, each of the said disks being provided with diametrically opposed rollers 298 adapted for engagement with the supports 295 for giving to the same movement in an upward direction, the weight of the supports 295 being relied upon to obtain descending 20 motion of the said supports. To the shaft 299 carrying a set of the disks 296 is affixed a crank arm 300, on which, in turn, is mounted a link 301 having an elongated recess 302 cooperating with a pin 303 mounted in one of the supports 295. It will be apparent that upon rotation of 25 the shaft 299 the rollers 298 will move the supports 295 upwardly, the link 301 being oscillated in a horizontal direction and co-operating with the supports 295 to move the same in properly timed relation in a horizontal direction, the cooperation of these parts effecting a substantial arcuate 30 movement of the feeder 294 to and from the magazine and trough, pneumatically controlled means 304 being provided operative when the feeder is at the magazine for selecting a plurality of stamps therefrom and operative when the feeder is adjacent the trough 281 to release the series 35 of stamps and to press these stamps against the gummed labels on the containers, the stamps in this manner being securely affixed in position on the labelled containers. Stop posts 305 are also preferably provided for limiting the horizontal motion of the supports 295 and the stamp feeder thereon. Motion may be supplied 40 to the disks 296 and 297 by means of a sprocket chain 306, movable over a sprocket 307 affixed to one of the disks 297, the sprocket chain 306 receiving motion from the main shaft 65.

After the stamp affixing operation the 65 row of containers stamped will be moved by one of the pusher arms 272 to further apparatus, the row formation of the containers being retained for further packaging operation. 70

The operation of my device will be, in the main, obvious from the description of structure and operation above detailed. It will be noted that rows of containers and rows of labels are fed respectively from 75 a container supply and a label supply to a label applying station, the rows of labels being adhesively coated while being fed to the label applying station, the labels being affixed to the containers, the containers being then fed in the maintained row formation to a gumming station and finally to a stamp applying station, where revenue stamps or the like may be affixed over the labelled containers. It will be further 80 noted that although rows of labels, containers and stamps go through this operating cycle, that parts of cycles of successive rows take place at the same time, this resulting in a high capacity output machine. 85 Thus, during the dwell period of the conveyer belts the label feeding means is transferring and depositing a row of labels on the belts, while at the same time a row of containers is moved into registration contact with a preceding row of labels at the label applying station, while simultaneously the two preceding rows of containers are about to undergo the steps of application 90 of the ends of the labels, while another row 100 is being discharged from the turret and moved into the trough, other rows being at this time operated upon at the gumming station F and the stamp applying station G. During motion of the conveyer belts a 105 new row of labels is being fed, a new row of containers moving into position at the label applying station, the turret moving for end label application to two rows of containers and other rows of containers moving over 110 the gumming means and moving into position for the stamp affixing operation. Thus a multiplicity of operations are taking place at one time considerably increasing the capacity of the machine. 115

While I have shown my device in the preferred form, it will be obvious that many changes and modifications may be made in the structure disclosed without departing from the spirit of the invention, defined in 120 the following claims.

I claim:

1. In a labeling machine, a label supply station, a pneumatic means for selecting a label from said supply station, a pneumatic device movable relatively to the pneumatic means for removing the label therefrom and for delivering the same to an adhesive ap- 125

plying station, and means at said adhesive applying station for adhesively coating the labels.

2. In a labeling machine, a label supply station, an adhesive applying mechanism, a pneumatic means for selecting a label from said supply station, a pneumatic device for removing the label from said pneumatic means and for transferring and depositing the same on the adhesive applying mechanism.

3. In a labeling machine, a magazine holding a supply of labels, a pneumatic means for selecting a label from said magazine, a pneumatic device for removing the label from said pneumatic means and for delivering the same to an adhesive applying station and means at said adhesive applying station for adhesively coating the labels.

4. In a gang labeling machine, a label supply station holding a plurality of stacks of labels, a pneumatic means comprising a plurality of elements for selecting a plurality of labels from said supply station, one from each stack, a pneumatic device for removing the said plurality of labels from said pneumatic means and for delivering the same to an adhesive applying station and means at said adhesive applying station for adhesively coating the labels.

5. In a gang labeling machine, a label supply station holding a plurality of stacks of labels, an adhesive applying mechanism, a pneumatic means comprising a plurality of elements for selecting a plurality of labels from said supply station, one from each stack, a pneumatic device for removing the plurality of labels from said pneumatic means and for transferring and depositing the same on the adhesive applying mechanism.

6. In a gang labeling machine, a label supply station holding a plurality of stacks of labels, a delivery means and a label applying means, a pneumatic means comprising a plurality of elements for selecting a plurality of labels from said supply station, one from each stack, a pneumatic device for removing the said plurality of labels from said pneumatic means and for delivering the same to the delivery means, the said delivery means being operative to deliver the labels to the label applying means.

7. In a labeling machine, a label supply station, an adhesive applying conveyer, a pneumatic means for selecting a label from said supply station, a pneumatic device for removing the label from said pneumatic means and for delivering the same to the adhesive applying conveyer.

8. The combination recited in claim 7, in which the adhesive applying conveyer includes provisions for conveying the label to a label applying station.

9. In a gang labeling machine, a label

supply station holding a plurality of stacks of labels, an adhesive applying conveyer, pneumatic means for selecting a plurality of labels from said supply station, a pneumatic device for removing the plurality of labels from said pneumatic means and for delivering the same to the adhesive applying conveyer.

10. In a labeling machine, a label supply magazine, an adhesive applying mechanism, a pneumatic picker reciprocable to and from the magazine for selecting a label therefrom and holding such label, a pneumatic transfer mechanism reciprocable to and from the pneumatic picker for removing the label from the picker and transferring it to the adhesive applying mechanism.

11. In a labeling machine, a label supply magazine, an adhesive applying mechanism, a pneumatic picker reciprocable in a vertical path to and from the magazine for selecting a label therefrom and holding such label, a pneumatic transfer mechanism reciprocable in a path at an angle to said vertical path and to and from the pneumatic picker for removing the label from the picker and transferring it to the adhesive applying mechanism.

12. In a labeling machine, a label supply magazine, an adhesive applying mechanism, a pneumatic picker reciprocable in a vertical path to and from the magazine for selecting a label therefrom and holding such label, a pneumatic transfer mechanism reciprocable in a horizontal path intersecting said vertical path and cooperating with said pneumatic picker for removing the label from the picker and transferring it to the adhesive applying mechanism.

13. In a labeling machine, a label supply magazine, an adhesive applying mechanism, a pneumatic picker located below said magazine and reciprocable to and from the magazine for selecting a label therefrom and holding such label, a pneumatic transfer mechanism reciprocable to and from the picker for removing the label from the picker and transferring it to the adhesive applying mechanism.

14. In a labeling machine, a label supply magazine, an adhesive applying mechanism, a pneumatic picker located below said magazine and reciprocable in a vertical path to and from the magazine for selecting a label therefrom and holding such label, a pneumatic transfer mechanism reciprocable in a horizontal path intersecting said vertical path and cooperating with said pneumatic picker for removing the label from the picker and transferring it to the adhesive applying mechanism.

15. In a labeling machine, a label supply magazine, an adhesive applying mechanism, a pneumatic picker located below said magazine and reciprocable in a vertical path to

- and from the magazine for selecting a label therefrom and holding the same, a pneumatic transfer mechanism reciprocable in a horizontal path and movable between the magazine and the picker for cooperation with the picker to remove the label therefrom and transfer the same to the adhesive applying mechanism.
16. In a labeling machine, in combination with a label applying mechanism, of a label supply magazine holding a stack of labels, a pneumatic picker movable to and from the magazine for selecting a label therefrom and holding the same, the picker being provided with a concave suction face adapted, when cooperating with the magazine, for the selection of a label to effect curling of the label for engagement with said face to facilitate segregating and withdrawal of the label from the magazine.
17. In a labeling machine, in combination with a label applying mechanism, a label supply magazine holding a stack of labels, the walls of said magazine being provided with lips protruding in the path of label movement and normally preventing such label movement, a pneumatic picker movable to and from the magazine for selecting a label therefrom and holding the same, the picker being provided with a concave suction face adapted, when cooperating with the magazine, for the selection of a label to effect curling of the label for engagement with said face and withdrawal of the same from engagement with the protruding lips.
18. In a labeling machine, in combination with a label applying mechanism, a label supply magazine holding a stack of elongated labels, the walls of said magazine being provided at its bottom with lips protruding in the path of label movement and normally preventing such label movement, a pneumatic picker movable to and from the magazine for selecting a label therefrom, the picker being provided with an elongated concave suction face adapted, when cooperating with the magazine, to form an elongated suction chamber to effect curling of the label and withdrawal of the same from engagement with the protruding lips in the magazine.
19. In a labeling machine, in combination with a label applying mechanism, a label supply magazine holding a stack of labels, a pneumatic picker movable to and from the magazine for selecting a label therefrom and holding the same, the picker being provided with a concave suction face, a pneumatic transfer mechanism movable to and from the picker, the pneumatic transfer mechanism being provided with a convex suction face cooperating with the concave suction face of the picker for removal of the label therefrom.
20. In a labeling machine, a label sup-
- ply magazine holding a stack of labels, an adhesive applying mechanism, a pneumatic picker movable to and from the magazine for selecting a label therefrom and holding the same, the picker being provided with a concave suction face, a pneumatic transfer mechanism movable to and from the picker, the pneumatic transfer mechanism being provided with a convex suction face, cooperating with the concave suction face of the picker for removal of the label therefrom and for depositing the same on the adhesive applying mechanism.
21. The combination recited in claim 20, in which the adhesive applying mechanism comprises a conveyer for conveying the label to a label applying station.
22. In a labeling machine, a label supply magazine holding a stack of labels, an adhesive applying mechanism, a pneumatic picker movable to and from the magazine for selecting a label therefrom and holding the same, the picker being provided with a suction face contoured to permit curling of the labels to facilitate segregating the same from the magazine, a pneumatic transfer mechanism movable to and from the picker, the pneumatic transfer mechanism being provided with a suction face complementary to the picker suction face and cooperating therewith for removal of the label therefrom and for depositing the same on the adhesive applying mechanism, the contour of the complementary suction face being such as to prevent any adhesive of the adhesive applying mechanism from reaching the transfer mechanism when cooperating therewith.
23. In a labeling machine, in combination with an adhesive applying mechanism, a label supply magazine, a pneumatic picker mechanism movable to and from the magazine for selecting a label therefrom and for holding such label, a pneumatically controlled transfer mechanism movable to and from the picker for removing the label from the picker and transferring it to a delivery station and means for releasing the pneumatic control of the picker mechanism including elements mounted for movement with both the picker and the transfer mechanism.
24. In a labeling machine, in combination with an adhesive applying mechanism, a label supply magazine, a pneumatic picker mechanism reciprocable to and from the magazine for selecting a label therefrom and for holding such label, a pneumatically controlled transfer mechanism reciprocable to and from the picker for removing the label from the picker and transferring it to a delivery station and means for releasing the pneumatic control of the picker mechanism including elements mounted for movement with both the picker and the transfer mechanism, the releasing means be-

ing set into operation by the positioning of one of the reciprocable mechanisms relative to the other.

25. In a labeling machine, in combination with an adhesive applying mechanism, a label supply magazine, a pneumatic picker mechanism reciprocable to and from the magazine for selecting a label therefrom and for holding such label, a pneumatically controlled transfer mechanism reciprocable to and from the picker for removing the label from the picker and transferring it to a delivery station, the picker mechanism being movable also to and from the transfer mechanism when the latter reaches a position adjacent the former, and means for releasing the pneumatic control of the picker mechanism including elements mounted for movement with both the picker and the transfer mechanism, the releasing means being set into operation by the movement of the picker with respect to the transfer mechanism.
26. In a labeling machine, a label supply magazine, an adhesive applying means, a pneumatically controlled picker mechanism movable to and from the magazine for selecting a label therefrom and for holding such label, a pneumatically controlled transfer mechanism movable to and from the picker for removing the label therefrom and transferring it to the adhesive applying means, means for releasing the pneumatic control of the picker mechanism including elements mounted for movement with both the picker and the transfer mechanism and means for releasing the pneumatic control of the transfer mechanism including an element mounted for movement with the said transfer mechanism.
27. In a labeling machine, a label supply magazine, a movable adhesive applying means, a pneumatically controlled picker mechanism movable to and from the magazine for selecting a label therefrom and for holding such label, a pneumatically controlled transfer mechanism movable to and from the picker for removing the label therefrom and transferring it to the adhesive applying means, means for releasing the pneumatic control of the picker mechanism including elements mounted for movement with both the picker and the transfer mechanism and means for releasing the pneumatic control of the transfer mechanism including elements mounted for movement with both the transfer mechanism and the movable adhesive applying means.
28. In a labeling machine, a label supply magazine, a movable adhesive applying means, a pneumatically controlled picker mechanism movable to and from the magazine for selecting a label therefrom and for holding such label, a pneumatically controlled transfer mechanism movable to and from the picker for removing the label therefrom and transferring it to the adhesive applying means, means for releasing the pneumatic control of the picker mechanism including elements mounted for reciprocation with both the picker and the transfer mechanism and means for releasing the pneumatic control of the transfer mechanism including elements mounted for movement with both the transfer mechanism and the movable adhesive applying means;
29. In a labeling machine, a label supply magazine, a reciprocable adhesive applying means, a pneumatically controlled picker mechanism reciprocable to and from the magazine for selecting a label therefrom and for holding such label, a pneumatically controlled transfer mechanism reciprocable to and from the picker for removing the label therefrom and transferring it to the adhesive applying means, means for releasing the pneumatic control of the picker mechanism including elements mounted for reciprocation with both the picker and the transfer mechanism and means for releasing the pneumatic control of the transfer mechanism including elements mounted for reciprocation with both the transfer mechanism and the reciprocable adhesive applying means, the first releasing means being set into operation by relative reciprocation of the transfer mechanism and the picker, the second releasing means being set into operation by relative reciprocation of the transfer mechanism and the reciprocable adhesive applying means.
30. In a labeling machine, a label supply magazine, a reciprocable adhesive applying means, a pneumatically controlled picker mechanism reciprocable to and from the magazine for selecting a label therefrom and for holding such label, a pneumatically controlled transfer mechanism reciprocable to and from the picker for removing the label therefrom and transferring it to the adhesive applying means, the picker mechanism being movable also to and from the transfer mechanism when the latter reaches a position adjacent the former, means for releasing the pneumatic control of the picker mechanism including elements mounted for reciprocation with both the picker and the transfer mechanism and means for releasing the pneumatic control of the transfer mechanism including elements mounted for movement with both the transfer mechanism and the movable adhesive applying means;

the first releasing means being set into operation by the movement of the picker with respect to the transfer mechanism, the second releasing means being set into operation by movement of the adhesive applying means with respect to the transfer mechanism.

31. The combination recited in claim 26, in which the adhesive applying means is a conveying adhesive applying system for applying adhesive to the labels and for conveying the same to a label applying station.

32. The combination recited in claim 19, in which the label supply magazine holds a plurality of stacks of labels and in which the picker mechanism comprises a gang of suction elements each having concave suction faces cooperating with the magazine and in which the transfer mechanism also comprises a gang of suction elements cooperating with the picker mechanism.

33. The combination recited in claim 23, in which the magazine holds a plurality of stacks of labels, in which the picker and the transfer mechanism comprise a gang of suction elements for simultaneously operating on a gang of labels and in which the releasing means comprises unitary provisions for releasing control of all the picker suction elements.

34. In a labeling machine, a label supply station, a pneumatic means for selecting a label from said supply station, a pneumatic device for removing the label from said pneumatic means and for delivering the same to an adhesive applying station and means for preventing cooperation of the pneumatic device with the adhesive applying station in the absence of proper selective activity of a label by said pneumatic means.

35. In a labeling machine, a label supply station, a pneumatic means for selecting a label from said supply station, a pneumatic device for removing the label from said pneumatic means and for delivering the same to an adhesive applying station and means for preventing cooperation of the pneumatic device with the adhesive applying station in the absence of proper activity of the pneumatic device in removing a label from the pneumatic means.

36. In a gang labeling machine, a label supply station holding a plurality of stacks of labels, a pneumatic means comprising a plurality of elements for selecting a plurality of labels from said supply station, one from each stack, a pneumatic device for removing the said plurality of labels from said pneumatic means and for delivering the same to an adhesive applying station and means for preventing cooperation of the pneumatic device with the adhesive applying station in the absence of proper selection by the pneumatic means of any one of the said plurality of labels.

37. In a gang labeling machine, a label

supply station holding a plurality of stacks of labels, a pneumatic means comprising a plurality of elements for selecting a plurality of labels from said supply station, one from each stack, a pneumatic device for removing the said plurality of labels from said pneumatic means and for delivering the same to an adhesive applying station and means for preventing cooperation of the pneumatic device with the adhesive applying station in the absence of proper activity of the pneumatic device in removing a label from the pneumatic means.

38. In a labeling machine, a label supply station, a pneumatic means for selecting a label from said supply station, a pneumatic device for removing the label from said pneumatic means and for delivering the same to an adhesive applying station and pneumatically controlled means for preventing cooperation of the pneumatic device with the adhesive applying station in the absence of proper selective activity of a label by said pneumatic means.

39. In a labeling machine, a label supply magazine, an adhesive applying means, a picker mechanism, means for moving said picker mechanism to and from the magazine for selecting a label therefrom and holding said label, a transfer mechanism, means for moving said transfer mechanism to and from overlying relation with respect to said picker for removing a label therefrom and transferring it to the adhesive applying means and provisions for moving said picker to and from the transfer mechanism when the latter is in said overlying relation with respect to the former to effect removal of the said label.

40. In a labeling machine, a label supply magazine, a delivery means, a picker mechanism, means for moving said picker mechanism to and from the magazine for selecting a label therefrom and holding said label, a transfer mechanism, means for moving said transfer mechanism to and from said picker for removing a label therefrom and for moving the same to the delivery means in overlying relation with respect thereto and provisions for moving said delivery means to and from the transfer mechanism when the latter is in said overlying relation with respect to the former to effect delivery of the said label.

41. In combination with the means recited in claim 40, means for preventing operation of said provisions in the absence of proper selective activity of said picker mechanism.

42. In combination with the means recited in claim 40, means for preventing operation of said provisions in the absence of proper removal activity of said transfer mechanism.

43. In combination with the means recited in claim 40, means for preventing operation of said provisions in the absence of proper

activity of either the picker or the transfer mechanism.

44. In a labeling machine, a label supply magazine, a movable adhesive applying means, a pneumatic picker mechanism, means for reciprocating said picker mechanism to and from the magazine for selecting a label therefrom and holding said label, a pneumatic transfer mechanism, means for reciprocating said transfer mechanism to and from said picker mechanism for removing a label therefrom, the transfer mechanism being movable into overlying relation with respect to the adhesive applying means, provisions for moving said adhesive applying means to and from the transfer mechanism for cooperation therewith and means for preventing operation of said provisions in the absence of proper selective or removal activity of either the picker or the transfer mechanism.

45. In a labeling machine, a label supply magazine, a movable adhesive applying means including a label conveyor, a label applying station, a pneumatic picker mechanism, means for reciprocating said picker mechanism to and from the magazine for selecting a label therefrom and holding said label, a pneumatic transfer mechanism, means for reciprocating said transfer mechanism to and from said picker mechanism for removing a label therefrom, the transfer mechanism being movable into overlying relation with respect to the adhesive applying means, provisions for moving said adhesive applying means to and from the transfer mechanism for cooperation therewith, means for preventing operation of said provisions in the absence of proper selective or removal activity of either the picker or the transfer mechanism and means for moving said conveyor to the label applying station.

46. The combination recited in claim 44, in which the last mentioned means comprises elements pneumatically controlled and set into operation by reciprocation of the transfer mechanism.

47. A gang labeling machine comprising means for feeding a row of containers to a label applying station, means for conveying a row of gummed labels to said label applying station, provisions for applying the row of labels to the row of containers, a label being applied to each container, elements for then conveying the row of labelled containers to a stamp applying station and means for applying a plurality of stamps to such labelled containers, a stamp being applied to each container.

48. A gang labeling machine comprising unitary means for feeding a row of containers to a label applying station, unitary means for conveying a row of gummed labels to said label applying station, provisions for applying the row of labels to the row of containers.

containers, a label being applied to each container, elements for then conveying the row of labelled containers to a stamp applying station and means for applying a plurality of stamps to such labelled containers, a stamp being applied to each container.

49. In combination with the means recited in claim 47, label feeding means for feeding a row of labels from a supply station to said label conveying means.

50. The combination recited in claim 49, in which the label conveying means is intermittently operated and in which the label feeding means and the label applying provisions are simultaneously operative during the dwell period of the label conveying means.

51. The combination recited in claim 49, in which the label conveying means comprises adhesively coated elements adapted to receive, coat and convey the row of labels.

52. A gang labeling machine comprising means for feeding a row of containers to a label applying station, means for conveying a row of labels to the label applying station, provisions for applying the row of labels to the row of containers, a label being applied to each container, and means for feeding a row of labels from a label supply station to the conveying means, the said conveying means comprising adhesively coated elements adapted to receive, coat and convey the row of labels.

53. The combination recited in claim 52, in which the conveying means is intermittently operated and in which the label feeding means and the label applying provisions are simultaneously operative during the dwell period of the label conveying means.

54. A labeling machine comprising means for feeding containers to a label applying station, intermittently operated means for conveying the labels to said label applying station, provisions for applying the labels to the containers, means controlled pneumatically for selecting labels from the label supply station and for feeding said labels to the conveying means, said conveying means comprising adhesively coated elements adapted to receive, coat and convey the said labels.

55. In combination with the means recited in claim 54, provisions also pneumatically controlled for preventing the label feeding means cooperating with the adhesively coated elements in the event of improper selection of labels by the said label feeding means.

56. In combination with the means recited in claim 53, means for continuously exerting impulses on the intermittently movable conveying means.

57. In a gang labeling machine, means for feeding a row of containers in a direction transverse to the length of the row to a label

applying station, means for feeding a row of labels in the direction transverse to the length of such row, means for receiving the row of labels from the label feeding means and for conveying the same in a direction parallel to the length of the row of labels to the label applying station, means for moving the row of containers into registration contact with the row of labels and provisions for applying the labels to the containers, a label being applied to each container.

58. The combination recited in claim 57, in which the conveying means comprises adhesively coated elements intermittently movable for receiving, coating and conveying the row of labels.

59. In combination with the means recited in claim 57, provisions for conveying the labelled containers to the stamp applying station, said provisions including an intermittently movable turret constructed and arranged to receive the rows of labels and transfer them to a discharge station.

60. The combination recited in claim 58, in which the means for feeding the labels, the means for moving the containers and the provisions for applying the labels are operative during the period of dwell of the conveying means.

61. In a gang labeling machine, means for moving a row of containers into registration contact with a row of adhesively coated labels, means for applying the labels to the containers, provisions for conveying the rows of labelled containers to a discharge station, means for moving the said row of labelled containers from said discharge station through a gumming station and to a stamp applying station, gumming means operative on the row of containers to apply gum or adhesive to a portion of the outer surface of the labels and means at the stamp applying station for applying a row of stamps to the row of containers, one stamp for each container.

62. The combination recited in claim 61, in which the provisions for conveying the rows of labelled containers comprise an intermittently operated turret.

63. The combination recited in claim 61, in which the means for applying the labels to the containers includes an element for partially applying the labels to the containers, said element being movable with the means for moving the containers into contact with the labels.

64. In a labeling machine, an adhesively coated conveyer carrying labels to a label applying station, means for moving containers into registration contact with said labels on the conveyer for withdrawal of the labels from the conveyer for label application and mechanism for resisting withdrawal of the labels to aid in the label ap-

plication, said mechanism including elements located adjacent ends of the labels normally out of contact with the same and means for effecting contact during label application.

65. In a labeling machine, spaced endless adhesively coated conveyers receiving labels and carrying them to a label applying station, means for moving containers in the space between the conveyers into registration contact with said labels on the conveyers for withdrawal of the same from the conveyers for label application and mechanism for resisting withdrawal of the labels to aid in label application, said mechanism including elements spaced similarly to said conveyers normally out of contact with the labels and means for effecting contact during label application.

66. The combination recited in claim 64, in which the adhesively coated conveyer carries sets of rows of labels and in which the means for moving the containers is constructed and arranged to move a row of containers into registration contact with a row of labels.

67. The combination recited in claim 64, in which the mechanism for resisting withdrawal of the labels includes resilient elements normally out of contact with the labels and provisions for moving the conveyer into contact with the resilient elements during label application.

68. In combination with the means recited in claim 64, means for partially applying the labels to the containers during the label withdrawing activity.

69. In combination with the means recited in claim 64, a carrier for receiving the labelled containers and for moving them to a discharge station.

70. The combination in claim 69, in which the carrier comprises an intermittently movable turret and in which the adhesively coated conveyer is intermittently moved synchronously with the intermittently movable turret.

71. In a labeling machine for applying a label about the walls of a container, a movable carrier, means for moving the container into registration contact with a label and into the carrier, means operative during such movement for partially applying the label about the walls of the container, the ends of the label remaining unattached, provisions in the path of movement of the carrier for applying one end of the label, said provisions being movable out of the path of movement of the carrier and mechanism for applying the other end of the label to the container.

72. The combination recited in claim 71, in which the movable carrier is constructed and arranged to receive a row of labelled containers and in which the means are con-

structed and arranged to effect label application of rows of containers.

73. The combination recited in claim 71, in which the said provisions are mounted for 5 movement with the means for moving the containers into contact with the labels.

74. The combination recited in claim 71, in which the mechanism for applying the other end of the label comprises means normally out of the path of movement of the 10 carrier and cam means on the carrier for operating said means to effect application of the said end.

75. In a labeling machine for applying a 15 label circumferentially about the walls of the container, an intermittently rotatable turret, reciprocable means for moving the container into registration contact with a label and into the turret during a dwell 20 period of the turret, means operative during such movement for partially applying the label about the walls of the container, the ends of the label remaining unattached and a plurality of elements on one side of 25 a diameter of said turret for effecting application of the ends of the labels, one of said elements operative by movement of the turret.

76. The combination recited in claim 75, 30 in which the other of said elements is mounted for reciprocation with the said reciprocable means.

77. The combination recited in claim 75, in which the other of said elements comprises 35 a rotating brush mounted for reciprocation with said reciprocable means.

78. In a labeling machine, means for applying opposite ends of the label in abutting or overlapping relation on a container, comprising a rotatable carrier holding a container and a label with unattached ends, means for rotating the carrier, provisions in 40 the path of movement of the container on the carrier for attaching an end of the label, 45 said provisions being movable out of the said path in the further movement of the carrier and further provisions in the path of movement of the container for attaching the other end of the label in abutting or overlapping 50 relation on the first end.

79. The combination recited in claim 78, in which the provisions comprises a rotatable brush and in which the further provisions comprises an oscillatable brush normally out of the path of movement of the 55 container and movable into such path by movement of the container.

80. In a gang labeling machine, a label supply magazine holding a plurality of 60 stacks of labels, an adhesive applying mechanism, a pneumatic picker reciprocable to and from the magazine for selecting labels therefrom and holding such labels, said picker being constructed and arranged 65 to select a row of labels from the magazine,

one from each stack, a pneumatic transfer mechanism reciprocable to and from the pneumatic picker for removing the row of labels from the picker and transferring it to the adhesive applying mechanism. 70

81. In a gang labeling machine, a label supply magazine holding a plurality of stacks of labels, an adhesive applying mechanism, a pneumatic picker reciprocable in a vertical path to and from the magazine for selecting labels therefrom, the picker being constructed and arranged to select a row of labels from the magazine, one from each stack, a pneumatic transfer mechanism reciprocable in the path at an 80 angle to said vertical path to and from the pneumatic picker and constructed and arranged for removing the row of labels from the picker and transferring it to the adhesive applying mechanism. 85

82. In a labeling machine, a label supply magazine holding a plurality of stacks of labels, an adhesive applying mechanism, a pneumatic picker reciprocable in a vertical path to and from the magazine and constructed and arranged for selecting a row of labels therefrom, one from each row, and holding such labels, a pneumatic transfer mechanism reciprocable in a horizontal path intersecting said vertical path and 90 constructed and arranged for cooperation with said pneumatic picker for removing the row of labels from the picker and transferring the same to the adhesive applying mechanism. 95

83. In a gang labeling machine, a label supply magazine holding a plurality of stacks of labels, an adhesive applying mechanism, a pneumatic picker located below said magazine and reciprocable to and from the 105 magazine, constructed and arranged for selecting a row of labels from the magazine, one from each stack, and holding such labels, a pneumatic transfer mechanism reciprocable to and from the picker and constructed and arranged for removing the row of labels from the picker and transferring them to the adhesive applying mechanism. 110

84. In a gang labeling machine, a label supply magazine holding a plurality of stacks of labels, an adhesive applying mechanism, a pneumatic picker located below said magazine and reciprocable in a vertical path to and from the magazine and constructed and arranged for selecting a row of labels from the said magazine, one from each stack, and holding such labels, a pneumatic transfer mechanism reciprocable in a horizontal path intersecting the 120 vertical path and cooperating with said pneumatic picker for removing the row of labels from the same and transferring them to the adhesive applying mechanism. 125

85. In a labeling machine, a label supply 130

- magazine holding a plurality of stacks of labels, an adhesive applying mechanism, a pneumatic picker located below said magazine and reciprocable in a vertical path to therefrom and holding such label, a transfer mechanism movable to and from the pneumatic picker and movable between the picker and the supply station for removing the label from the picker and transferring it to the adhesive applying mechanism. 35
- 5 and from the magazine and constructed and arranged for selecting a row of labels from the magazine, one from each stack, and holding the same, a pneumatic transfer mechanism reciprocable in a horizontal path 40
- 10 and movable between the magazine and the picker and constructed and arranged for cooperation with the picker to remove the row of labels therefrom and transfer the same to the adhesive applying mechanism. 45
- 15 86. In a labeling machine, a label supply station, an adhesive applying conveyer, a pneumatic means for selecting a label from said supply station, a transfer mechanism for removing the label from said pneumatic means and for delivering the same to the adhesive applying conveyer. 50
- 20 87. In a gang labeling machine, a label supply station holding a plurality of stacks of labels, an adhesive applying conveyer, a plurality of labels from such supply station, one for each stack, a device for removing the plurality of labels from said pneumatic means and for delivering the same to an adhesive applying station, the said device 55
- 25 being movable to and from the pneumatic means and between the label supply station and the said pneumatic means. 60
- 30 88. In a labeling machine, a label supply station, an adhesive applying mechanism, a pneumatic picker reciprocable to and from the magazine for selecting a label 65

Signed at New York, in the county of New York and State of New York, this 7th day of February A. D. 1921.

JONATHAN PETERSON.
